UNITED STATES PATENT OFFICE.

CARLTON RIDDLE, OF AKRON, OHIO.

JACKETED VESSEL.

1,133,821.

Specification of Letters Patent. Patented Mar. 30, 1915.

Application filed December 15, 1913. Serial No. 806,938.

To all whom it may concern:

Be it known that I, CARLTON RIDDLE, a citizen of the United States, residing at Akron, in the county of Summit and State of Ohio, have invented a certain new and useful Improvement in Jacketed Vessels, of which the following is a full, clear, and exact description, reference being had to the accompanying drawings.

10 This invention relates to the construction of jacketed vessels designed for digesting, heating, evaporating or impregnating substances.

15 One of its objects is to provide such a vessel, the inner shell of which is designed to stand both internal and external pressure and will greatly relieve the strain at the joints, due to sudden expansion of either the internal or external shell.

20 Another object is to eliminate the necessity of stay bolts, commonly used between the two shells of such a vessel.

25 My invention is hereinafter more fully described in connection with the drawings, and the essential characteristics set forth in the claims.

Figure 1 is a central vertical section through a digesting apparatus, illustrating my invention; Fig. 2 is a horizontal section.

30 The digesting tank comprises a cylindrical outer shell 5 suitably welded at its upper edge to the outer periphery of a ring 6. At its lower edge it is suitably welded to the upwardly projecting flange 8, of the convex plate 9, which has a central opening in its bottom portion in which is welded a ring 10. Within this shell 5 is a substantially cylindrical corrugated shell 12, preferably made of suitable boiler plate welded at its upper edge 14 to the inner periphery of the ring 6 and at its lower edge to the upturned flange 15 of a convex downwardly extending inner bottom 16 having a central opening, the edge of which is secured to the upper side of the partially convex ring 10. The corrugations of the inner shell are circumferential, and are coarse so that the shell is made longitudinally elastic. The bottom 16 is spaced away from the bottom 10 to provide a suitable steam space between them, which communicates with the steam space 17 between the two shells 5 and 12. The outwardly extending portions 18 of the corrugated shell 12 are suitably spaced from the cylindrical shell 5 to permit free passage of steam. A steam inlet leading to this steam

space is indicated at 20 near the upper part of the shell. A drip for the water from the condensed steam may be provided at 22 near the lower portion of the bottom shell 9. Now the inner shell is closed at its upper side by an upwardly extending convex plate 23 having a downwardly turned flange 24 riveted to the inside of the upper edge of the inner shell, thus inclosing the inner shell. 65 A manhole 25 is made in the plate 23 surrounded by an outwardly turned flange and adapted to be closed by a cover 26 drawn upwardly by means of bolts 27 extending through a clamp 28, having its two arms in 70 engagement with the plate at either side of the manhole. The removal of this cover allows the admission of the substance to be digested. An inlet for admitting steam for digesting, to the inner shell may be provided 75 at 29 in the plate 23.

Fitted into the inner periphery of the ring 10 is a cylindrical portion 30 of the valve body 31, having a projecting annular flange 32 adapted to be removably secured 80 to the ring by suitable screws. The passage 34 of this valve body opens upwardly into the inner shell and is provided with a suitable valve seat which is engaged by a valve head 35 adapted to close this opening and 85 carried on a valve stem 36, slideable in a guide 38 made rigid with the valve body. At the lower end of the guide 38 is an outwardly projecting flange 39 adapted to be engaged by a ring 40 having an annular 90 groove engaging this flange and a flange 42 of a threaded hub 43 of a hand wheel 45. The wheel is rotatably carried by the flange and is thereby prevented from end movement, providing for raising and lowering 95 the valve stem 36, which is threaded into this hub, when the hand wheel is rotated. The valve body is preferably elbow-shaped and is provided with an annular flange 47 to which may be connected a pipe leading 100 from the valve. This provides a removable connection at this point allowing access to the valve head and valve seat so that they may be cleaned by hand. It also provides for keeping these parts clear of obstructions 105 which might prevent free discharge of the substance within the vessel.

As a means for agitating the contents of the vessel, I provide a vertical shaft 50 journaled in a suitable bearing 51 having an outwardly projecting flange 52 secured to the plate 23 and at its lower end, in a bearing 54

carried on a strip 55 extending across the inner shell and having its ends turned to the side, as at 56, and suitably secured to the lower portion of this shell. The upper bearing is provided with a stuffing box of the usual form having packing 58 engaging the shaft 50 and compressed by the member 59 surrounding the shaft and adapted to be drawn toward the member 51 by screws 60. 5

10 A pinion 62 carried by a shaft 63 and meshing with a beveled gear 64, rigid with the upper end of the shaft 50, provides a suitable means for rotating it. Any number of paddles may be secured to this shaft 50. As 15 shown, I have provided a rectangular paddle 64 secured to the shaft by means of a clamp 66 above the bearing 54 and below this bearing is provided a paddle 65 secured to the shaft in the same manner, having a horizontal upper edge. Its lower edge conforms to the shape of the inner bottom 16 and moves in a path adjacent thereto. At its middle portion a large notch 67 is cut through its lower side to allow the raising movement of 20 the valve head 35. A collar 68 secured to the shaft 50 by means of a set screw 69 prevents the shaft sliding downwardly and holds the bevel gears in engagement.

The vessel may be supported in any suitable manner. As shown I have provided four right angled brackets 70 secured to the outer shell 5 by means of rivets 71. These may rest upon any suitable support, such as the floor of a room, providing convenient 35 access to the upper part of the casing for filling the digester through the manhole 25, and providing convenient access to the valve at the bottom, from the room below.

Now in operation, any desirable material 40 may be dumped into the vessel through the manhole 25, which is then closed. The space between the jackets is supplied with steam through the port 20 and steam for digesting may be supplied to the interior of the vessel 45 by the port 29. At the beginning of the operation, the pressure on the outside of the inner shell is very apt to be greater than the pressure within said shell, and later in the operation the steam pressure used for digesting is apt to be superior to the pressure between the shells, also the steam pressure 50 between the shells remains constant during the discharging and filling operations, at which time there is no pressure within the 55 inner shell. The circumferential corrugations of the inner shell greatly strengthen it to resist this wide variation in pressure. These conditions also cause at times, great 60 differences in the temperature of the two shells, and during the filling operation the cold material coming in contact with the inner shell constantly cools it while the outer shell remains hot. The differences in 65 temperature of the two shells, causes one to expand or contract much more than the

other, which would ordinarily be very injurious to the joints, straining them and causing them to leak. With my invention, however, the corrugations of the inner shell provide a longitudinal elasticity which relieves the strain at the joints, and prevents them becoming loosened. 70

It will be seen from the foregoing description that I have provided a construction for digesting and heating tanks of this 75 character, the shells of which are adapted to withstand great differences in pressure, and the joints of which shall be constantly steam tight because there is no great strain on them due to sudden contraction or expansion of their shells. It will be further seen that the device is conveniently arranged and easy to operate. It provides for rapidly discharging matter therein and is easily accessible for cleaning. 80

Having thus described my invention, what I claim is:

1. The combination of an outer shell, a corrugated inner shell spaced from the outer shell and connected therewith at the upper 90 end, end members for the inner and outer shells spaced apart and each having a central opening, a ring secured in said opening and a valve mounted in said ring, a closure for the other end of the inner shell, a bearing 95 centrally mounted thereon, a transverse member carried by the inner shell and having a bearing, a shaft mounted in said bearing, an agitator on said shaft, there being an opening through the upper end member of 100 the inner shell, and a closure for said opening.

2. The combination of an outer shell, an end member closing one end of said shell, a corrugated inner shell secured to the outer 105 shell at its upper end and spaced from the outer shell, an end member parallel with the end member of the outer shell and adjacent thereto, central openings through the adjacent end members of the inner and outer 110 shells, a ring mounted between the end members at the opening, said end members overlapping the same, a valve carried by said ring and adapted to open inwardly into the inner shell, a closure for the upper end of 115 the inner shell having a downwardly turned flange fitting inside said shell, an opening in said closure surrounded by an inwardly turned flange, a closure for said opening adapted to be drawn upwardly against said 120 flange, and means for securing the same in position.

3. The combination of a cylindrical outer shell, a ring secured to the inside of one end of said shell, a corrugated inner shell fitting the inner periphery of said ring, dome-shaped closures for the lower end of each shell, each closure having an upwardly turned flange secured to its respective shell, 125 said closures being parallel and separated 130

- forming a space communicating with the space between said inner and outer shells, registering openings in each of said closures, a ring mounted between the closures and at 5 said openings, a valve carried by said ring, a closure for the other end of the inner shell having a downwardly turned flange secured to the inner end thereof, means for supplying steam pressure to the interior of the inner shell, means for supplying steam pressure 10 to the space between said shells, and means for agitating matter in the interior of the inner shell.
4. The combination of an outer shell, a 15 corrugated inner shell spaced from the outer shell and connected therewith at the upper
- end, end members for the inner and outer shells spaced apart, a closure for the other end of the inner shell, a bearing centrally mounted thereon and provided with a stuffing box, a shaft extending through said stuffing box, an agitator carried on said shaft, means for rotating the shaft, and independent means for admitting pressure to the interior of the inner shell and to the 20 space between the shells.
- In testimony whereof, I hereunto affix my signature in the presence of two witnesses.
- CARLTON RIDDELE.
